J. J. REINHOLD

DOOR RETAINER

Filed March 10, 1923

Patented Sept. 22, 1925.

1,554,828

UNITED STATES PATENT OFFICE.

JOHN J. REINHOLD, OF MARIETTA, PENNSYLVANIA.

DOOR RETAINER.

Application filed March 10, 1923. Serial No. 624,162.

To all whom it may concern:

Be it known that I, JOHN J. REINHOLD, a citizen of the United States, and a resident of Marietta, county of Lancaster, State of

5 Pennsylvania, have invented certain new and useful Improvements in Door Retainers, of which the following is a specification.

This invention relates to door retainers for holding swinging doors in certain positions against movement from anomalous 10 causes.

The object of this invention is to provide a door retainer which can be conveniently adjusted to hold the door in various positions. This door retainer has no dependence whatever upon the floor of the room for its operation; and the door may be moved in either direction by simply applying a slight excess pressure against it.

20 A further object is to provide adjustable means for limiting the movement of the latching lever so that the same cannot inadvertently get to a position where it would be inconvenient to make adjustments.

25 This invention will be more fully understood and other objects will be apparent from the following description, taken in connection with the accompanying drawing, forming a part hereof, and in which similar 30 numerals refer to similar parts throughout the several views.

Fig. 1, is a front elevation of my door retainer and represents one form of my invention.

35 Fig. 2, is a plan view of Fig. 1.

Fig. 3, is a sectional view of Fig. 1, taken on line 3—3.

With reference to the drawing, 4 is a bracket fixed to the door frame 3, through 40 the screws 6. Forming part of the bracket 4 are bosses 7 and 8 which carries the pin 5. The lever 10 is fixed to the pin 5 through the key pin 27. The flange 26 forms part of the lever 10 and is provided with a series 45 of holes 11. Forming part of the boss 7 is a casing 9 which carries the stop pin 12. The stop pin 12 is normally held in engagement with one of the series of holes 11, through the spring 14, and thereby locks 50 the lever 10 against movement. The free end of the lever 10 is provided with a groove 15 which is adapted to receive the plunger 16. The plunger 16 is carried by the bracket 17 which is fixed to the door 18 through 55 the screws 19. The plunger 16 carries a stem 20 which protrudes through the bracket

17; to this stem is fixed a set collar 21 which limits the upward movement of the plunger. The spring 22 normally holds the plunger 16 in the uppermost position.

60 The manipulation of this device consists of pulling momentarily on the ring 23 or cord 24, thereby withdrawing the stop pin 12 and again engaging it with any hole of the series 11, and consequently locking the 65 lever 10 at the proper position for retaining the door 18 in the desired position; one of these positions being shown in light broken lines, Fig. 2. The door will then be held in this position against movement from anomalous causes so long as the plunger 16 is in engagement with the groove 15. The spring 22 resists inward movement of the plunger 16 sufficiently to produce this result. The 70 spring 22 however should be yielding to 75 such extent whereby the plunger 16 will disengage with the groove 15 when ordinary pressure is applied to the door by a person passing through the same in the ordinary manner. The edges of the lever 10 80 are turned upward as shown at 25 to permit easy entrance of the plunger 16 into the groove 15.

To render this device inoperative for an indefinite period it is only necessary to engage the ring 23 with a nail or hook fixed to the door frame in a manner whereby the stop pin 12 is withdrawn and held from 85 engaging any of the holes 11. This may be done when the plunger 16 is engaged with 90 the groove 15, in which event the lever 10 will move with any movement of the door; or if the plunger 16 is not engaged with the 95 groove 15 the lever 10 may rest in any position, but preferably at the extreme open position of the door.

There may be certain times when the door cannot be opened to the full extent, for instance, on account of there being a piece of furniture located against the wall along 100 side the door, as shown at 28 in light broken lines; this piece of furniture would limit the opening movement of the door, but not the movement of the lever 10. Under such circumstances if the lever 10 should inadvertently get beyond the opening limit of the door, it would be inconvenient to adjust the lever, because ordinarily it is beyond the reach of the average person unless they stand on something in the nature of a chair 105 or step-ladder. Therefore to avoid a condition of this kind means are provided to 110

limit the movement of the lever 10 in this direction, as follows:—The boss 7 is provided with an extension 29, around which fits a collar 30. Forming part of the collar 30 is a lug 31, adapted to engage with the lug 32 forming part of the pin 5. A wing head screw 34 is provided to lock the collar 30 in various positions on the extension 29. Through this construction the turning movement of the lever 10 is limited at the point where the lug 32 contacts with the lug 31, and it is obvious that this point may be altered by turning the collar 30 on the extension 29.

15. Since the door 18 swings around a different central point from that of the lever 10 it will be observed that the plunger 16 will have a sliding action in the groove 15, if the same is permitted to remain therein 20 while the stop pin 12 is withdrawn and the door is in motion. Therefore the groove 15 must be of sufficient length to accommodate to the full extent the sliding movement produced when the door is fully opened, and 25 also for the purpose of assuring that there will be a groove present to engage with the plunger 16 regardless of the position in which the lever 10 might be locked.

Having thus described my invention, what 30 I claim and desire to secure by Letters Patent is as follows:

1. In a door retainer comprising a bracket,

a lever pivotally secured to said bracket, means for locking said lever in various positions to said bracket, and a latching device 35 for connecting the end of said lever to the door, said latching device being spring pressed and yielding to permit disconnection of said door from said lever end when a marked effort is applied in moving said door. 40

2. In a door retainer comprising a bracket, a lever pivotally secured to said bracket, means for locking said lever in various positions to said bracket, means whereby the end of said lever may be latched to the door 45 and hold the same against movement from ordinary anomalous causes, and means for limiting the movement of said lever in a direction to correspond to the opening movement of the door. 50

3. In a door retainer comprising a bracket, a lever pivotally secured to said bracket, means for locking said lever in various positions to said bracket, means whereby the end of said lever may be latched to the door 55 and hold the same against movement from ordinary anomalous causes, and means for limiting the movement of said lever in a direction to correspond to the opening movement of the door, the same being capable of 60 adjustment to alter said limited point of lever movement.

In testimony whereof I affix my signature.
JOHN J. REINHOLD.
